UNITED STATES PATENT OFFICE.

JOSEPH A. GROEBLI, OF NEW YORK, N. Y., ASSIGNOR TO KURSHEEDT MANUFACTURING COMPANY, OF NEW YORK, N. Y., A CORPORATION OF NEW YORK.

STOP MECHANISM FOR EMBROIDERING MACHINES.

No. 911,235.

Specification of Letters Patent.

Patented Feb. 2, 1909.

Application filed January 25, 1907. Serial No. 354,089.

To all whom it may concern:

Be it known that I, JOSEPH A. GROEBLI, a citizen of the United States, residing at New York, in the county of New York and State of New York, have invented new and useful Improvements in Stop Mechanism for Embroidering-Machines, of which the following is a specification.

My invention relates to stop mechanism for embroidering machines and has for its object to produce means whereby the actuating mechanism for the needle mechanism or other group of devices flexibly driven may be brought to rest promptly when such mechanism goes out of action.

In a general way the mechanism which I have shown solely by way of example in the drawing, relates in this particular instance generally to the mechanism shown, described and claimed in U. S. Letters Patent No. 593,208, dated Nov. 9, 1897, for embroidery machine.

The invention, broadly stated, consists of means for bringing the actuating mechanism for effecting certain functions in the embroidery machine promptly to rest, and is especially adapted for use and combination with such mechanism as may be "flexibly" driven, such, for instance, as trains of gearing whose infirmities are well known.

The invention also consists of means for braking a driving mechanism where a disconnecting mechanism having several parts with "play" between them are employed for effecting the disconnection and it is in this sense that I desire my claims also to be read.

In the drawing: Figure 1 is a plan view partly in section of a mechanism in which my invention is embodied, showing the same in its initial position. Fig. 2 is a sectional side elevation on line 2—2 of Fig. 1, looking in the direction of the arrow: Fig. 3 is a transverse section on line 3—3 of Fig. 1 looking in the direction of the arrow: Fig. 4 is a detail perspective side view of a hooked slide coöperating with the actuating arm to actuate and to restore certain movable parts to position, also showing another slide coöperating therewith to effect the braking: Fig. 5 is a detail side view of the hooked slide shown in Fig. 4: Fig. 6 is a plan view of the same: Fig. 7 is a side view of the other slide shown in Fig. 4: Fig. 8 is a plan view of the same: Fig. 9 is a plan view on a slightly enlarged scale of part of the mechanism shown in Fig.

1 illustrating the parts in their operating position: Fig. 10 is a transverse sectional elevation of some of the parts shown in Fig. 9 clearly showing the transmission train, the section being taken on line 10—10 of Fig. 9 looking in the direction of the arrow: Fig. 11 is a sectional elevation on line 11—11 of Fig. 9 looking in the direction of the arrow: Fig. 12 is a perspective view of an operating piece for effecting the unlocking or release of the actuating bar from the brake arm: Fig. 13 is a detail perspective of the unlocking pins and one of the guides for the brake actuating slide: and Fig. 14 is a detail perspective view of the unlocking bar for actuating the locking pin.

In the drawing wherever practicable I have lettered parts corresponding to parts in the Letters Patent hereinbefore referred to by the same reference letters as are used in the said patent.

In the drawing K indicates a multiple armed lever corresponding to the lever K in said patent. This lever actuates and governs the disconnecting mechanism for the needle mechanism of the embroidery machine, and the actuating and release mechanism for the brake arm. C indicates the cam shaft of the machine having the cam C¹ with which the lever K coöperates, being adapted to be rocked by the cam-slot c in the cam C¹. Mounted upon the shaft C is a bevel gear D which meshes with a bevel pinion E on the shaft F of the machine. The shaft F carries a gear G which meshes with a gear H on the cam-shaft I for the needle motion. This train of transmission gears constitutes in a sense a "flexible" drive due to back-lash and wear. Mounted on the shaft I is a cam or wheel L against whose periphery a brake shoe M is adapted to be pressed to brake the cam or wheel L to bring the same to rest promptly.

The brake shoe M is carried by a brake arm a pivoted at b to a bracket d on the main frame e of the machine. This arm a is of considerable length and its free end rests upon a spring-support or ledge f. The long arm of the brake arm a is adapted to be actuated in one direction to apply the brake by the following mechanism:

The main operating or controlling mechanism for the brake arm a is a pair of slides g, i which work side by side in guides j and which slides are shown in detail in Figs. 4 to 8 inclusive. The slide g operates to apply the

brake and may be described as follows, it being premised that the said slide is given a reciprocating operative movement to the left as shown in Figs. 9 and 10. The slide g has a bevel nose g^1 and an abutment or lug g^2 which is adapted to come against the brake arm a when the slide is moved forward, as will be explained. The slide g is also provided with a stop g^3 , an abutment g^4 , to effect the restoration of the slide, and an arm g^5 for the attachment of a spring.

The slide i is provided with a nose i^2 and a hook i^3 adapted to coöperate with slide moving mechanism, such as the pin k^7 on the arm k^5 . The slide i is also provided with a lateral guide-lug i^4 and a lug i^5 having a pin i^6 for the attachment of a spring. The slides g and i are connected by a stiff spring k^{10} .

The arm K receives its movement from an arm k^2 forming part thereof which has a bowl or piece k^3 which is entered into the cam-slot c in the cam C^1 by the jacquard or otherwise at predetermined times and is, as aforesaid, part of the disconnecting mechanism for part of the sewing mechanism. An arm or link k^4 leads from the arm and forms part of the adjusting for part of the embroidery mechanism. The arm K is also provided with an operating arm k^5 having a cam k^6 . This cam k^6 has a portion between the letters $x-x$ which is concentric with the axis of the shaft carrying the arm K . The cam k^6 bears against the nose i^2 to actuate the slides g and i . Pin k^7 on arm k^5 takes behind the hook i^3 to restore the slides to their initial positions.

Pivoted at k^8 to the arm k^5 is an operating piece l having a bowl or lug l^1 bearing against a cam c^2 on the shaft C (see Figs. 10 and 12). The operating piece l is provided with an actuating or cam arm l^3 adapted to bear against shoulders, lugs or pins m^1 m^2 on a release or unlocking bar m (see Figs. 10 and 14) to advance or withdraw the bar m . The operating piece is also provided with a stop arm l^4 adapted to contact with a stop shoulder m^3 and with a lug l^5 one of whose functions is to guide the operating piece l in its movement by contacting with the side of the stop shoulder m^3 . The bar m moves in a guide m^4 and is provided with a rack m^5 meshing with what in the present instance may be termed a guide pinion m^6 in the guide m^4 . The bar m is provided with a lifting nose or cam m^7 which is adapted to contact with the lower end of a pin m^8 (see Figs. 10, 11 and 13) which works vertically in the guide j having a slotted shank j^2 which is integral with or supported by a plate j^3 on the frame of the machine. The vertically movable pin m^8 has a lateral pin or abutment m^9 upon which the slide g (for operating the brake arm or lever a) rests. (See Fig. 11.) For simplicity in illustration I have not shown in this case the means for connecting

and disconnecting the transmission gear, because that is fully shown and described in my Patent No. 593,208, hereinabove referred to. In that patent the arm K carries a lever which operates a connecting means and a rack and pinion arrangement is provided for initiating the movement of the gear D . As the construction there shown and described may be bodily used with the present invention it is believed that further reference to that device is unnecessary here.

The detailed operation of the structure shown and described as constituting one form of construction in which my invention is embodied may be said to be as follows: Starting with the parts in the positions shown in Figs. 1, 2 and 3, entrance of the piece k^3 on the arm k^2 into the cam slot c in the cam C^1 , which may be effected from the jacquard or otherwise, as will be readily understood will cause the arm k^5 to swing to the left, Fig. 3, and the cam k^6 thereon will ride against the nose i^2 of the slide i thus moving said slide to the left carrying with it the slide g by reason of the stiff spring connection k^{10} between the slides g and i . This, as the movement continues, will, by the action of nose g^1 of slide g rising on the brake lever a , bring the lug or abutment g^2 in contact with said brake arm a and apply the brake M to the cam or wheel L on the operating shaft I ; the disconnection of the transmission gear having taken place meantime through the action of the device shown in my U. S. patent herein referred to. Continued forward movement of the arm k^5 and slide g will operate to supply the brake to the cam or wheel L by what is virtually a positive movement. This will bring the cam L and its connected parts to rest at once. The nose i^2 now rests against the portion $x-x$ of the cam k that is to say on a dead center. About this time the operating piece l will be brought into action to unlock the slide g from the brake lever to release the said brake lever and brake; the restoring spring a^1 of the brake lever a effecting the restoring action of said brake lever. This is done as follows: When the lever k^5 has operated the slides g and i , the operating piece l will be positioned for action. At this time the cam c^2 will act upon said piece l to swing it, the rotation of the shaft C being so timed as to effect this result. During this time the nose i^2 of slide i will rest against the concentric portion $x-x$ of the lever k^5 . As the operating piece l swings on its pivot k^8 its cam arm l^3 bears against the shoulder m^1 (see Figs. 10 and 14) of the unlocking bar m and causes its nose m^7 to raise the pin m^8 thereby raising the pin m^9 (see Figs. 11 and 13) and lifting the slide g with its lug or abutment g^2 (see Fig. 10) clear of the brake lever a which is thereupon restored to its initial position, see dotted 1

and full lines in Fig. 9. The slides etc. are returned from their positions shown in Figs. 9, 10 and 11 to their initial positions shown in Figs. 1, 2, and 3. The slides *i* and *g* are 5 restored thus. As the arm *k*⁵ executes a reverse swing the hook *i*³ on the slide *i* will be engaged by the pin *k*⁷ on the arm *k*⁵ and will travel with it engaging the abutment *i*⁵ on slide *i* behind the abutment *g*⁴ on slide *g* 10 and retracting the slide *g*. The operating piece *l* will thereby also execute a reverse swing and act upon the abutment *m*² on the unlocking bar *m* to retract the said bar and thereby lower the pins *m*⁸ and *m*⁹. The parts 15 are now in the positions shown in Fig. 3 and are ready for another operation.

Having described my invention what I claim and desire to secure by Letters Patent is:—

20 1. In an embroidering machine, the combination of main and supplemental means for driving a part of the embroidering machine, gears for transmitting power from the main to the supplemental driving means, 25 means for disconnecting the transmitting means from the main driving means and a brake operating upon the supplemental drive and adapted to be actuated by the said disconnecting means.

30 2. In an embroidering machine, the combination of a main and a supplemental driving means for a part of the embroidering machine, gears for transmitting power between said driving means, disconnecting mechanism therefor, and brake mechanism operating 35 on the supplemental drive and independent of the transmission gears and means for actuating said brake mechanism, initiated from the disconnecting mechanism.

40 3. In an embroidering machine the combination of main and supplemental means for driving a part of the embroidering machine, brake mechanism adapted to operate upon said supplemental drive and means 45 whereby the power from said main drive will operate to set the brake mechanism and means operated from the said main drive for releasing the said brake mechanism.

4. In an embroidering machine the combination of a main and a supplemental drive for a part of the embroidering machine, means for transmitting power between said drives, brake mechanism adapted to operate on the supplemental drive, means operated 55 by the main drive, adapted to disconnect said main and supplemental drives and adapted to set the said brake mechanism and means carried by said disconnecting means and operated from the said main 60 drive, adapted to release said brake mechanism.

5. In a stop motion for embroidering machines, the combination of a brake, a disconnecting mechanism for disconnecting part 65 of the embroidering machine and an actuat-

ing mechanism intervening between the disconnecting mechanism and the brake, and comprising in its structure a plurality of cooperating reciprocating slides one of which interlocks with the brake mechanism and 70 means for actuating the slides from the disconnecting mechanism, and means for moving a slide laterally to unlock or release the brake device.

6. In a stop motion for embroidering machines, the combination of a driving means, 75 and a brake device therefor, an oscillating member adapted to disconnect a part of the driving means of the embroidering machine, means operated by said disconnecting means 80 in one of its oscillations and adapted to operate said brake device and means operated by a part of the driving mechanism and adapted to release said brake device before the reverse oscillation of said disconnecting 85 member.

7. In a stop motion for embroidering machines, the combination of a driving means and a brake device therefor, an oscillating lever adapted to disconnect a part of the 90 driving mechanism of the embroidering machine, reciprocating slides one of which is adapted to engage and operate said brake device, said slides being adapted to be reciprocated by said oscillating lever and means operated by a part of the driving mechanism adapted to release said operating slide from the brake device before the return of the said oscillating lever.

8. In a stop motion for embroidering machines, the combination of driving mechanism for part of the embroidering machine, a 100 brake device, actuating mechanism therefor, a locking device engaging with the brake device, an operating piece for operating to unlock said brake operating device, means for positioning said unlocking piece for operation and means operated by a part of the driving mechanism and adapted to operate 105 said unlocking piece.

9. In an embroidering machine, a driving mechanism, a brake mechanism therefor, actuating mechanism for the brake mechanism, unlocking mechanism for said brake operating device, common means for operating 115 the said brake actuating mechanism and for positioning the said unlocking mechanism for operation and means for operating said unlocking mechanism.

10. In an embroidering machine, a driving 120 mechanism, a brake mechanism therefor, actuating mechanism for the brake mechanism, releasing mechanism for said brake operating device, common means for operating the said brake actuating mechanism and for 125 positioning the said releasing mechanism for operation and means operated by the said driving device for operating said releasing mechanism.

11. In an embroidering machine, the com- 130

1
bination of main and supplemental means for driving part of the embroidering machine, means for transmitting power between the said driving means, means operated by said main drive adapted to disconnect said main and supplemental drives and brake mechanism operating on said supplemental driving means.

12. In an embroidering machine, the combination of main and supplemental means for driving part of the embroidering machine, means for transmitting power between the said driving means, means operated by said main drive adapted to disconnect said main and supplemental drives, and brake mechanism operating on said supplemental driving means and adapted to be initiated from the said disconnecting mechanism.

13. In an embroidering machine, the combination of main and supplemental driving means for part of the embroidering machine, means for transmitting power between the said driving means, and brake mechanism operating on said supplemental drive, and means whereby the said brake will receive its operating action from the main driving means.

14. In an embroidering machine, the combination of a normally operating main drive, a supplemental drive and means for transmitting power from the main to the supplemental drive, means operated by said main

drive, and during the continuance of its operation, adapted to disconnect said main and supplemental drives and a brake mechanism 35 operating on the supplemental drive and adapted to be initiated by said disconnecting mechanism.

15. In an embroidering machine, the combination of a main and a supplemental driving means for part of the embroidering machine, means for transmitting power between the said driving means, means for disconnecting said drives, a brake mechanism operating on said supplemental drive and 45 means whereby the said brake mechanism will receive its operating force from the main drive.

16. In an embroidering machine, the combination of a main drive, means for transmitting power from the main drive to the embroidering machine, mechanism operated by the main drive for disconnecting the power transmitting means and a brake mechanism initiated by the disconnecting mechanism 50 and adapted to operate upon a part of the disconnected mechanism.

Signed at New York, in the county of New York, this 24th day of January 1907.

JOSEPH A. GROEBLI.
